UNITED STATES PATENT OFFICE

2,055,998

CAN SEAMING MACHINE

Frank W. Burpee, Chicago, Ill., assignor to Burpee Can Sealer Company, Chicago, Ill., a corporation of Illinois

Application October 27, 1934, Serial No. 750,277

12 Claims. (Cl. 113—23)

This invention relates to the art of can seaming machines, having reference more particularly to hand operated machines designed for domestic canning operations, and more particularly to a known type of such machines wherein the seaming roller or rollers are actuated in properly timed relation by and from the means by which the chucks or like devices that hold the can and its cover are actuated during the seaming operation, so that the machine can be operated by one hand.

One object of the invention is to provide a simplified and improved mechanism whereby both the chucks and the seaming roller or rollers can be operated by and from the chuck-actuating crank.

My present improvements are applicable to a machine adapted to seal cans of a single or uniform diameter, and also machines adapted to seam cans of varying diameters and employing a plurality of chuck devices for holding the cans, machines of the latter type being typically illustrated in my former Patents 1,486,225, March 11, 1924, and 1,959,018, May 15, 1934; and in this application I have shown my improvements applied to a machine of the type shown in the last-named patent. A further object of the invention, as applied to a machine of that type is to provide a new and improved means for locking each arm of the chuck carrier in correct working position when the chuck carried thereby has been adjusted to correct position for cooperation with the can seaming roller or rollers.

Still other objects and attendant advantages of the invention will be apparent to persons familiar with this art as the same becomes better understood by reference to the following detailed description, taken in connection with the accompanying drawings wherein I have illustrated one practical and approved embodiment of the principle of the invention, and in which:

Fig. 1 is a side elevation of the machine showing the smaller of the two driven chucks in working position and the seaming rollers in correct position for the start of the seaming operation.

Fig. 2 is a top plan view of Fig. 1.

Fig. 3 is a rear elevational view of the upper portion of Fig. 1.

Fig. 4 is a front elevation of the upper portion of the machine, showing the two upper chucks reversed as to position and the pivoted locking bar and seaming roller actuating mechanism carried thereby swung upwardly to admit the larger chuck to working position.

Fig. 5 is a cross sectional detail taken on the line 5—5 of Fig. 2.

Fig. 6 is a cross sectional detail taken on the offset line 6—6 of Fig. 2.

Fig. 7 is a fragmentary plan view on an enlarged scale showing index devices for determining the correct starting position.

I will first describe those structural features of the present machine that are substantially identical with the machine of my Patent 1,959,018, and I will then proceed to describe the novel improvements forming the chief subject matter of the present invention.

Referring to the drawings, the machine employs a generally rectangular frame comprising a base bar 10, spaced uprights 11 and 12 on said base bar, and a horizontal top bar 13 connecting and rigidly spacing the upper ends of the uprights 11 and 12. Revolubly mounted on the upper shouldered end of the upright 12 is a chuck carrier formed with oppositely extending arms 14 and 15 directly beneath and parallel with the top bar 13. Pivotally mounted in the end portions of the arms 14 and 15 are upper chucks 16 and 17 respectively, the former being of a lesser diameter than the latter. The peripheral edges of these chucks, as usual in machines of this type, are formed to engage the inner side of the recess of the can cover adjacent to the beading edge, and are knurled to effect a driving hold on the can cover when the latter is pressed upwardly into engagement with the chuck. It will be observed that the axes of rotation of the two chucks 16 and 17 are at different distances from the axis of rotation of the chuck carrier, the purpose of this being to bring the peripheral edge of each chuck into correct working relation to the can seaming mechanism hereinafter described. Rigidly secured on the upper sides of the chuck 16 and 17 are driven bevel gears 18 and 19 respectively.

Journaled on the shouldered upper end of the frame upright 11 is the hub 20 of a seaming roller carrier or support 21, on which latter are journaled the primary and secondary seaming rollers 22 and 23 and also, preferably, a cutting roller 24 which may be employed for cutting off the top of a previously filled and sealed can to empty the contents of the latter. For hand manipulation of the cutting roller 24 the support 21 is equipped with a handle 25.

Mounted on the base bar 10 is a slide 26, secured on which is a post 27. A lower chuck 28 has a hub 29 slidable and rotatable on the post 27. Beneath and supporting the lower end of the hub 55

29 is a cam 30 adapted to be engaged by a cross pin 31 in the post 27. On the cam 30 is a handle 32 by which the cam is rotated to thereby, through cooperation with the pin 31, raise or 5 lower the chuck 28. The slide 26 is normally locked stationary relatively to the base 10 by a machine screw 33 extending through a slot 34 in the slide and screwed into the base 10. The other slightly raised end of the slide 26 rests on 10 one of a pair of clamp brackets 35 by which the machine is mounted on a table or bench 36 and is equipped with a pair of upstanding lugs 37, between which operates an eccentric cam 38 fast on the lower end of a sleeve 39 that is rotatable 15 on the frame upright 12 and at its upper end is keyed to the chuck carrier. From the foregoing it will be seen that when the clamp screw 33 is loosened and the chuck carrier is rotated, the slide 26 will be simultaneously shifted endwise to 20 carry the axis of the lower chuck 28 into registry with the axis of whichever chuck 16 or 17 is in working position. The chuck plate 28 is of proper diameter to engage with the shallow recess in the bottom of the larger diameter can body. When 25 operating on the smaller diameter can, the chuck 28 is covered by an adapter 28' formed with a low can-engaging head 40 that fits the smaller can.

Turning now to a description of my present 30 improvements, 41 designates as an entirety a locking bar of inverted U-shape in cross section that surmounts the top bar 13 of the frame, the side walls thereof being sufficiently deep to straddle not only the top bar 13, but the underlying arm 14 or 15 of the chuck carrier. The front wall of this locking bar is formed with a longitudinal slot 42 (Fig. 1) through which extends a threaded pivot stud 43 that is screwed into a tapped hole in the top bar 13. When the 35 two chucks are reversed, it is necessary to shift the locking bar a slight distance endwise, and it is also necessary to swing the locking bar upwardly out of the way (as shown in Fig. 4). This construction permits both of these movements.

Referring to Figs. 2 and 5, in the front wall of the locking bar 41 is mounted a stud 44 on which is journaled a drive pinion 45 adapted to mesh with either of the driven gears 18 and 19 of the two chucks. Fast with the hub of the pinion 45 40 is a crank arm 46 equipped with a handle 47.

On the top sides of the chucks 16 and 17 and encircling the driven gears 18 and 19 thereof, are spiral gears 48 and 49. In the rear side wall of the locking bar 41 is mounted a pivot stud 50 45 (Fig. 6) journaled on which is a gear 51 having inclined teeth that are engaged by the spiral gears 48 and 49. The construction is such that a complete rotation of the spiral gear rotates the gear 51 one tooth. In the rear side of the gear 51 is mounted a stud 52 on which is journaled a cam roller or follower 53, best shown in Fig. 3. In the rear wall of the locking bar 41 are mounted a pair of spaced studs 54 that form supports for a reciprocable bar 55 which is formed with slots 56 50 that ride on the studs 54. This bar 55 is further formed with a cam slot 57 that is engaged by the cam follower 53 and is so designed as to effect reciprocating movements of the bar 55 from the continuous rotary movement of the gear 51. One 55 end of the bar 55 is forked and apertured as shown at 55' to receive one end of a link 58, the other end of which link is pivoted at 59 to a short radial arm 60 on the hub 20 of the seaming roller support 21. Since the locking bar 41 and parts 60 carried thereby require to be shifted endwise

when adjusting the machine to receive cans of a different diameter, the length of the operating connection between the gear 51 and the arm 60 of the seaming mechanism must be correspondingly adjusted and this is effected by providing two spaced holes 61 and 62 (Fig. 2) in the link 58, the former of which is engaged by the removable threaded pin 63 when the smaller diameter chuck is in working position, and the latter by the same pin when the larger diameter chuck is in working 10 position.

A clamp screw 64 extending through a hole in the top wall of the locking bar 41 engages with one or the other of a pair of tapped holes 65 in the top bar 13 to thereby lock the said locking bar 15 and the gears 45 and 51 that are journaled thereon in working position.

Referring to Figs. 2 and 7, the top wall of the locking bar 41 is preferably supplied with an index mark such as the arrow 66, and one of the teeth of the gear 51 is supplied with a cooperating index mark such as the groove 67 formed in one of the gear teeth.

In the operation of the machine, the handle 46 is first turned until the index mark 67 registers with the index mark 66. In this position the primary and secondary seaming rollers 22 and 23 are sufficiently spaced from the upper chuck 16 or 17 to permit the chucking of the can, which is done by simply placing the can and loosely applied end on the lower chuck and swinging the handle 32 to raise the top of the can into register with the upper chuck and securely clamp the can between the two chucks. The crank 46 is then turned clockwise, viewing Fig. 1 which first sets up a slow inward travel of the reciprocating bar 55 and its associated link 58, thus causing the primary seaming roller 22 to approach and engage with the periphery of the can cover to be seamed. Continued rotation of the crank 46 40 then causes an outward movement of bar 55 and link 58, which retracts the primary seaming roller and causes the secondary roller 23 to approach and engage with the periphery of the can cover, effecting the final sealing operation. Still further rotation of the crank 46 again causes an inward movement of bar 55 and its link 58, bringing both seaming rollers substantially into the starting position wherein both are spaced from the sealed edge of the can so that the lower 45 chuck can be lowered and the sealed can removed.

When it is desired to operate the machine with the other chuck in working position, the pins 63 and 64 are both withdrawn. This disconnects the link 58 from the bar 55, and the link may be swung to one side as indicated by dotted lines in Fig. 2. The clamp pin 64 having been withdrawn from the top bar 13, the locking bar 41 and the parts carried thereby can be swung upwardly and rearwardly on the stud 43 as a pivot 60 to the position shown in Fig. 4. The chuck carrier is then swung through 180 degrees which, at the same time, shifts the lower chuck to proper position to cooperate with the different diameter can, the locking bar is then lowered and at the same time shifted endwise to the required extent to accurately position the drive pinion 45 for engagement with the driven gear on the chuck, the clamp pin 64 is reapplied, and the link 58 is again connected to the bar 55 by the pin 63. 70 The crank is then turned to bring the index markers 66 and 67 into registry, the can is chucked, and the described cycle is then repeated.

When it may be desired to open a previously filled and sealed can, the link 58 is first discon-

nected from the bar 55, the roller support 21 is then swung by the handle 25 to a position wherein the cutting roller 24 lies adjacent to the upper chuck, the can is then chucked and rotated and simultaneously the cutting roller 24 is pressed against the wall of the can by the handle 25, severing the wall of the can just below the lid or cover.

It is believed that the foregoing description, 10 in connection with the drawings, will make clear how the machine effectuates the stated purposes and objects of the invention. The old practice of pressing the seaming rollers into cooperative engagement with the periphery of 15 the can cover with one hand, while rotating the chuck with the other, is done away with, and the seaming rollers are automatically operated in proper sequence by and from the turning of the chuck crank alone, thereby substantially simplifying 20 the operation of the machine. The described locking bar not only serves as a carrier for the drive pinion 45 and the transmission gear 51, and as a support for the movement-transmitting bar 55, but, by reason of the fact 25 that its side walls are sufficiently deep to straddle both the top bar 13 and the chuck carrier arm 14 or 15, it serves to accurately align the said parts and prevents any lateral play of the carrier arm during the operation of the machine. 30 This invention may be developed within the scope of the following claims without departing from its essential features, and the specification and drawings are to be read as merely illustrative and not in a limiting sense, except as necessitated by the prior art.

I claim:

1. In a can seaming machine, the combination with a suitable frame, upper and lower chucks rotatably mounted therein, a seaming roller support journaled on said frame, and a seaming roller journaled on said support, of means for rotating one of said chucks, a reciprocable member operatively connected at one end thereof to said support, a gear on said upper chuck, and means driven by said gear for reciprocating said reciprocable member when said upper chuck is rotated.

2. In a can seaming machine, the combination with a suitable frame, upper and lower chucks rotatably mounted therein, a seaming roller support journaled on said frame, and a seaming roller journaled on said support, of means for rotating one of said chucks, a reciprocable member operatively connected at one end thereof to said support, a spiral gear on said upper chuck, a second gear engaged with and driven by said spiral gear, and operating means for said reciprocable member between said second gear and said reciprocable member and actuated by said second gear.

3. In a can seaming machine, the combination with a suitable frame, upper and lower chucks rotatably mounted therein, a seaming roller support journaled on said frame, and a seaming roller journaled on said support, of means for rotating one of said chucks, a reciprocable member operatively connected at one end thereof to said support, a cam on said reciprocable member, a spiral gear on said upper chuck, a second gear engaged with and driven by said spiral gear, and a cam follower on said second gear engaged with said cam.

4. In a can seaming machine, the combination with a suitable frame, upper and lower chucks rotatably mounted therein, a seaming roller sup-

port journaled on said frame, and a seaming roller journaled on said support, of means for rotating one of said chucks, a slidably supported bar having a cam slot, a link pivoted at one end to said bar and at its other end to said support, a spiral gear on said upper chuck, a second gear engaged with and driven by said spiral gear, and a cam follower on said second gear engaged with said cam slot.

5. In a can seaming machine, the combination 10 of a frame including a top bar, a chuck carrier pivotally mounted on said frame formed with radially extending arms each movable to a position parallel with and underlying said top bar, chucks of different diameters pivotally mounted 15 respectively on said arms at different distances from the axis of rotation of said chuck carrier, gears adapted to be driven on the respective chucks, a locking bar of inverted U-shape in cross-section surmounting said top bar, the sides whereof are adapted to straddle said top bar and an underlying arm of said chuck carrier, means for securing said locking bar in adjusted position on said top bar, and a drive pinion and operating crank therefor mounted on said locking bar. 20

6. In a can seaming machine, the combination 25 of a frame including a top bar, a chuck carrier pivotally mounted on said frame formed with radially extending arms each movable to a position parallel with and underlying said top bar, chucks of different diameters pivotally mounted 30 respectively on said arms at different distances from the axis of rotation of said chuck carrier, gears adapted to be driven on the respective chucks, an endwise shiftable locking bar of inverted U-shape in cross-section pivotally mounted 35 on said top bar, the sides whereof are adapted to straddle said top bar and an underlying arm of said chuck carrier, a clamp screw extending through a wall of said locking bar and engaged 40 with a tapped hole in said top bar, and a drive pinion and operating crank therefor journaled on a side wall of said locking bar. 45

7. In a can seaming machine, the combination 50 with a suitable frame, of can seaming means including a seaming roller and a support therefor pivotally mounted on a member of said frame, a plurality of rotatable upper chucks of different diameters carried by said frame each bodily movable into and out of position to cooperate with 55 said can seaming means, chuck rotating means, a gear on each of said chucks, a lengthwise adjustable reciprocable member operatively connected at one end thereof to said support, and means engaged with and driven by the gear of the chuck 60 in can seaming position for actuating said reciprocable member when said last named chuck is rotated.

8. In a can seaming machine, the combination 65 with a suitable frame, of can seaming means including a seaming roller and a support therefor pivotally mounted on a member of said frame, a plurality of rotatable upper chucks of different diameters carried by said frame each bodily movable into and out of position to cooperate with said can seaming means, a gear adapted to be driven and a spiral gear on each of said chucks, a lengthwise adjustable reciprocable member operatively connected at one end thereof to said support, bodily shiftable means engaged with and driven 70 by the spiral gear of the chuck in can seaming position for actuating said reciprocable member when said last named chuck is rotated, a bodily shiftable drive pinion adapted to engage with the driven gear of a chuck when the latter is in can 75

seaming position, means for locking each chuck in can seaming position.

9. In a can seaming machine, the combination of a frame having a top bar, can seaming means including a seaming roller and a support therefor pivotally mounted on a member of said frame, a chuck carrier pivotally mounted on said frame formed with radially extending arms each movable to a position parallel with and underlying said top bar, chucks of different diameters pivotally mounted respectively on said arms at different distances from the axis of rotation of said chuck carrier, a gear adapted to be driven and a spiral gear on each of said chucks, a lengthwise adjustable locking bar of inverted U-shape in cross section surmounting said top bar, the sides whereof are adapted to straddle said top bar and an underlying arm of said chuck carrier, a lengthwise adjustable reciprocable member slidably supported on said locking bar and operatively connected at one end thereof to said support, a gear mounted on said locking bar engaged with and driven by the spiral gear of the chuck in can seaming position, a cam on said reciprocable member, a cam follower mounted on said last-named gear engaged with said cam, a drive pinion mounted on said locking bar adapted to engage with the driven gear of a chuck when the latter is in can seaming position, and means for locking said locking bar in adjusted position.
10. In a can seaming machine, the combination of a frame having a top bar, can seaming means including a seaming roller and a support therefor pivotally mounted on a member of said frame, a chuck carrier pivotally mounted on said frame formed with radially extending arms each movable to a position parallel with and underlying said top bar, chucks of different diameters pivotally mounted respectively on said arms at different distances from the axis of rotation of said chuck carrier, a gear adapted to be driven and a spiral

gear on each of said chucks, a lengthwise adjustable locking bar of inverted U-shape in cross section pivotally mounted on said top bar, the sides whereof are adapted to straddle said top bar and an underlying arm of said chuck carrier, a lengthwise adjustable reciprocable member slidably supported on said locking bar and operatively connected at one end thereof to said support, a gear mounted on said locking bar engaged with and driven by the spiral gear of the chuck in can seaming position, a cam on said reciprocable member, a cam follower mounted on said last-named gear engaged with said cam, a drive pinion mounted on said locking bar adapted to engage with the driven gear of a chuck when the latter is in can seaming position, and means for locking said locking bar in adjusted position.

11. In a can seaming machine, the combination with a suitable frame, upper and lower chucks rotatably mounted therein, a seaming roller support journaled on said frame, and a seaming roller journaled on said support, of means for rotating one of said chucks, a reciprocable member operatively connected at one end thereof to said support, and power transmitting means from said upper chuck to said reciprocable member actuated by said upper chuck for reciprocating said member when said upper chuck is rotated.

12. In a can seaming machine, the combination with a suitable frame, upper and lower chucks rotatably mounted therein, a seaming roller support journaled on said frame, and a seaming roller journaled on said support, of means for rotating one of said chucks, a slidably supported bar, a link pivoted at one end to said bar and at its other end to said support, and power transmitting means from said upper chuck to said bar operated by said upper chuck for reciprocating said bar when said upper chuck is rotated.

FRANK W. BURPEE. 40
